US0D1099124S

(12) **United States Design Patent** (10) **Patent No.:** **US D1,099,124 S**
(45) **Date of Patent:** **** Oct. 21, 2025**

(54) **DISPLAY SCREEN WITH GRAPHICAL USER INTERFACE**

Primary Examiner — Rachel A. Voorhies

(71) Applicant: **CALYX, INC.**, Berkeley, CA (US)

(57)

CLAIM

(72) Inventors: **Po-Jui Chiu**, Taipei (TW); **I-Ting Chen**, Taipei (TW); **Tsung-Lin Lu**, Taipei (TW); **Shu-Ting Chang**, Taipei (TW)

The ornamental design for a display screen with a graphical user interface, as shown and described.

(73) Assignee: **CALYX, INC.**, Berkeley, CA (US)

DESCRIPTION

(**) Term: **15 Years**

(21) Appl. No.: **29/893,616**

(22) Filed: **Jun. 1, 2023**

FIG. 1 is a front view of a first image in a sequence of a display screen with a graphical user interface, showing our new design;

(51) LOC (15) Cl. **14-04**

FIG. 2 is a front view of a second image thereof;

(52) U.S. Cl.

FIG. 3 is a front view of a third image thereof;

USPC **D14/485**

FIG. 4 is a front view of a fourth image thereof;

(58) Field of Classification Search

FIG. 5 is an enlarged view of the portion labeled 5 in FIG. 3;

USPC ..... D14/485—495
CPC G06F 3/048; G06F 3/0482; G06F 3/04817;
H04M 1/724—72484

FIG. 6 is an enlarged view of the portion labeled 6 in FIG. 3; and,

H04M 1/724—72484

FIG. 7 is an enlarged view of the portion labeled 7 in FIG. 4.

See application file for complete search history.
